UNITED STATES PATENT OFFICE

MAE HUSEBOE AND REUBEN W. PORTER, OF LOS ANGELES, CALIFORNIA

DESIGN FOR A PRINTING PLATE OR SIMILAR ARTICLE

Application filed September 17, 1930. Serial No. 37,005. Term of patent 14 years.

To all whom it may concern:

Be it known that we, MAE HUSEBOE and REUBEN W. PORTER, both citizens of the United States, residing at Los Angeles, in the county of Los Angeles and State of California, have invented a new, original, and ornamental Design for a Printing Plate or Similar Article, of which the following is a specification, reference being had to the accompanying drawing, forming part thereof.

The figure is an elevation of a printing plate or similar article, showing our new design.

The article has no appreciable thickness.

We claim:

The ornamental design for a printing plate or similar article, as shown and described.

MAE HUSEBOE.
REUBEN W. PORTER.
